UNITED STATES PATENT OFFICE.

JOHN P. EDMONDS, OF SCOTTSBORO, ALABAMA.

FLOAT OR SIGNAL-BUOY FOR SUNKEN VESSELS.

1,269,798.

Specification of Letters Patent. Patented June 18, 1918.

Application filed February 6, 1918. Serial No. 215,623.

To all whom it may concern:

Be it known that I, JOHN P. EDMONDS, a citizen of the United States, residing at Scottsboro, in the county of Jackson, State 5 of Alabama, have invented a new and useful Float or Signal-Buoy for Sunken Vessels; and I do hereby declare the following to be a full, clear, and exact description of the invention, such as will enable others skilled 10 in the art to which it appertains to make and use the same.

This invention relates to a float or signal buoy for locating sunken vessels, and one of the objects of the invention is the provision 15 of a depending loop carried by the float or buoy signal having suitable bearings for the shaft of a reel, about which a cable (which has one end attached to the deck of the vessel) is wound, whereby as the vessel 20 sinks the buoy will float on the surface of the water, as the cable unreels, thereby signaling the location of the sunken vessel.

A further object of the invention is the provision of improved supporting means 25 carried by the deck of the vessel for the reception of said depending loop of the buoy, whereby the buoy may be held in a perpendicular position, so that it may remain on the surface of the water as the vessel sinks.

30 One of the features of the invention is the provision of a support for the floating buoy, said support being tapering or conical and in skeleton form and constructed of sheet metal, the upper parts of the sides of the 35 support being braced by sheet metal straps while the lower parts of the sides are provided with sheet metal supporting legs, hence insuring a light durable and practical support.

40 In practical fields the details of construction may necessitate alterations falling within the scope of what is claimed.

The invention comprises further features and combination of parts as hereinafter set forth, shown in the drawings and claimed.

45 In the drawings:—

Figure 1 is a view in side elevation of a sunken ship or vessel, showing the float or signal buoy floating on the surface of the 50 water.

Fig. 2 is a detail perspective view of float or signal buoy.

Fig. 3 is a detail perspective view of the skeleton sheet metal support for the depend- 55 ing loop of the float or signal buoy.

Fig. 4 is a vertical sectional view through

the support and the buoy, showing the latter supported in the former.

Fig. 5 is a cross sectional view on line 5—5 of Fig. 4.

Fig. 6 is a detail view of a portion of the cable to be connected to the deck of the vessel and in turn wound about the reel of the float or buoy, showing the heart of the cable being in the form of a telephone wire, where- 65 by should the signal be carried by a submarine telephone connections may be had with the crew of the sunken submarine.

Referring more especially to the drawings 70 1 designates a sunken vessel, and 2 a support which is in skeleton form as shown. The body of the support is constructed from a piece of sheet metal bent upon itself as at 3 substantially midway its end. The end portions of the sheet metal are disposed V- 75 shaped, thereby forming the sides of the support as tapering downwardly toward each other to the point 3. The sides of the support are bent at slight obtuse angles as shown at 4, thereby forming the substantially perpendicular parallel parts or extensions 5. The sides of the support, at right angles to the V-shaped arrangement of the sides are each slightly tapered, and the opposite edges of both sides are provided with 80 right angle flanges 6. These flanges 6 originate from the edges of the sides at a point a short distance above the bend 3. A rectangular sheet metal strap 7 fits over the upper end portions of the sides, and is secured by 85 the rivets 8, thereby reinforcing the sides of the support relative to each other, the flanges 6 acting to additionally reinforce and strengthen the sides.

Sheet metal legs 9 have their anchoring 95 extensions 10 secured by rivets 11 to the V-shaped arranged sides of the support, and the bodies of the legs incline outwardly and downwardly, and their lateral feet 12 are secured by rivets or the like 13 to the deck 14 100 of the vessel. The float or signal buoy comprises a tapering or conical hollow body 15, which is constructed of sheet metal and provided with upper and lower sheet metal ends 16 and 17. The end pieces 16 and 17 105 are provided with marginal overturned flanges 18 and 19, which receive and engage the flanges 20 and 21 of the opposite ends of the body 15. These inter-engaging flanges are clenched tightly together to insure air 110 tight joints between the parts, thereby providing a float or buoy, the interior chamber

of which is air tight. A suitable sheet metal strap is bent upon itself to form a tapering loop 22 and the lower tapered end of this loop has an opening 23 through which a cable 24 passes. The loop 22 is tapered and constructed correspondingly to and capable of fitting the support, and the obtuse angle extensions 25 of the sides of the loop 22 are secured by rivets or the like 26 to the float 5 or buoy. A suitable shaft 27 is mounted in bearings 28 in the sides of the loop, and mounted on and rotatable with the shaft is a reel or drum 29. One end of the shaft has a crank 30, whereby the drum or reel may 10 be rotated, for winding the cable 24 (one end of which is attached to the drum and its other end to an eye 31 on the deck of the vessel) on the drum, whereby the loop 22 of the float or buoy may be supported 15 in the support without interference from the cable. The cable, a section of which is illustrated in Fig. 6 has its heart consisting of a telephone wire 32, which is insulated, so that should the signal float or buoy 20 be carried by a submarine, a telephone may be connected to the upper end of the cable, for communication with the crew of the sunken submarine. As the vessel sinks, the float or buoy automatically leaves its support 25 and remains on the surface, while the cable unreels or unwinds from the drum, the buoy or float remaining on the surface of the water acting as a signal for indicating the location of the sunken vessel. 30

35 The invention having been set forth what is claimed as new and useful is:—

1. The combination with a signal buoy, of a supporting socket therefor, being constructed from a single piece of sheet metal 40 bent upon itself midway its ends forming

sides arranged V-shaped, the edges of the sides having strengthening flanges, a rectangular sheet metal strap connecting the upper ends of said sides, and supporting legs connected to the sides, adapted to be 45 secured to the deck of a vessel.

2. The combination with a supporting socket, of a signal buoy, the body of the buoy being tapered, a socket receiving member formed from a single piece of sheet 50 metal, bent upon itself to provide sides, the upper ends of which being secured to the body of the buoy, the sheet metal being so constructed at the lower end of said member as to provide an opening, a drum having pintles mounted in the sides of the member, and on which a cable is adapted to be wound, whereby the buoy may be attached to the deck of a vessel.

3. The combination with a signal buoy 60 of a supporting socket therefor adapted to receive the lower end of said buoy, said supporting socket being constructed from a single piece of sheet metal bent upon itself midway its ends forming sides arranged V-shaped, the edges of the sides having strengthening flanges extending toward each other to prevent lateral movement of the lower end of the buoy, and a rectangular band being connected to the upper ends of 70 the sides to hold them rigid, and means to support the socket on the deck of a vessel.

In testimony whereof I have signed my name to this specification in the presence of two subscribing witnesses.

JOHN P. EDMONDS.
